(57) **CLAIM**

The ornamental design for a pressure washer nozzle, as shown and described.

DESCRIPTION

FIG. 1 is a front, right, and top perspective view of a Pressure washer nozzle, showing my design.

FIG. 2 is a rear, left, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines shown in the drawings are included for the purpose of illustrating portions of the pressure washer nozzle that form no part of the claimed design.

1 Claim, 8 Drawing Sheets(56)
